CLAIM

The ornamental design for an analyte detection device as shown and described.

DESCRIPTION

FIG. 1 is a perspective view of an analyte detection device showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view thereof shown in a configuration of use.

The broken lines showing an applicator in FIG. 8 illustrate environment and form no part of the claimed design. The remaining broken lines in the drawings illustrate portions of the analyte detection device that form no part of the claimed design.
